METHOD OF DEVELOPING OIL FIELDS

Henry L. Doherty, New York, N. Y.

Original application May 22, 1925, Serial No. 31,996. Divided and this application October 19, 1932, Serial No. 638,505

2 Claims. (Cl. 166—21)

This invention relates to the art of recovering petroleum, and particularly to improved flow control valves adapted for regulating the inflow of oil to well tubing. The present invention was 5 originally described in my copending patent application Serial No. 31,996,—of which this is a division.

The present methods of production or of extracting oil from the ground are very inefficient. The accepted estimate of expert geologists and production engineers show that in many localities the present methods of oil production do not recover much more than 20% of the oil in sand.

When oil wells are first put to producing, there is obtained a higher initial production than is obtained later. This high initial production has been primarily attributed to the high gas pressure prevailing in the oil sands at the time the oil wells are first projected therein, it being well known that the expulsive energy of the gas increases as the square of the pressure.

Though it is known that gas pressure is an important controlling influence in drainage of oil sands and that every effort should be made by the operator to conserve the gas and permit it to flow from the oil reservoir only in sufficient quantity to secure oil production, it is seldom that the operator has found it to his interest to conserve the gas for the reason that the operator usually has control of but a very limited portion of the oil field acreage, the surrounding acreage usually being held by other and competing operators. Where the oil field is controlled by different operators it can be readily appreciated that the operator who first gets his well into the oil body will usually obtain the largest oil production by reason of the fact that the initial production is always higher than later on when the gas pressure has been reduced and the gas dissipated. If the operator of the first well projected into the oil body should seek to conserve the gas and to reduce the quantity escaping to that necessary to produce oil, he would be acting against his own interest because by maintaining the back pressure in the well, the gas would be free to carry oil out to the adjacent surrounding wells of competitors.

From the above remarks, it will be readily appreciated that the ideal method of developing an oil field would be to have the same under the control of one operator or one responsible authority so that proper conservation of the gas and the maintenance of back pressure in the wells 55 could be maintained to the end that the maxi-

mum extraction of the oil from the oil sands would be had.

With the above facts in view it is a primary object of the invention to provide an improved oil recovery apparatus by which a high percentage of oil may be recovered from an oil sand without the economic wastes which result from the present method of production. 5

Another object of the invention is to provide a method of producing oil by which the escape 10 of gas with the oil may be held to minimum.

A still further object of the invention is to provide a method and apparatus by which the gas pressure at the bottom of the well may be determined. 15

With these and other objects in view the invention consists in the improved methods of and apparatus for developing oil fields hereby described and particularly defined in the appended claims. 20

I have discovered that there is another very important factor besides the expulsive energy of the compressed gas which determines the amount of oil that can be extracted from the oil sands. I have found that the viscosity of crude oil varies 25 indirectly with the amount of natural gas dissolved or absorbed therein,—in other words, the fluidity of the oil varies directly with the amount of gas dissolved or absorbed in the oil. Inasmuch as a less viscous oil moves through the oil sand 30 with less resistance, it can be readily appreciated that the discovery is of the utmost importance and that an additional reason is offered for the conservation of the gas in the oil field. The dissolved gas also causes a material lowering of the 35 surface tension of the oil.

Referring to the drawings forming part of this specification:

Fig. 1 is a vertical sectional view diagrammatically illustrating the positioning of wells in an oil 40 field of the dome type;

Fig. 2 is a chart containing three heavy line curves showing relation between relative viscosity of crude oil containing dissolved gas under pressure and cubic feet of gas dissolved 45 per barrel of oil.

Fig. 3 is a vertical section through an oil well showing means for ascertaining the pressure of the gas at the bottom of the well and for regulating the flow of the oil; and 50

Fig. 4 is an enlarged sectional detail view of the valve mechanism at the bottom of the well above the packer through which the oil and gas must pass before passing up and out through the top of the well. 55

As already indicated, I have discovered that the viscosity of the oil is materially lowered depending upon the amount of gas dissolved or absorbed therein. By reference to Fig. 2 it will be seen how the viscosity of the oil varies with the amount of dissolved natural gas therein. Curves *a* and *b* are based on the same grade of crude oil but on a natural gas of different methane content. Both curves show that the viscosity decreases as the amount of gas dissolved in the oil increases, and of course the amount of gas which is dissolved in the oil varies directly as the pressure. In curve *a* the methane content of the natural gas is approximately 52% while in curve *b* it is approximately 82%. The other constituents of natural gas such as ethane, propane and butane are more soluble in the oil than methane and hence render the oil less viscous. In any event it will be seen that the amount of gas dissolved in the oil has a material bearing on its viscosity and hence of the ease with which it will flow through the oil sands. Curve *c* is based on a different grade of crude oil but on the same methane content of the gas as curve *b*. Curve *c* shows, therefore, that different oils have a different viscosity with the same amount of gas dissolved therein.

Inasmuch as the viscosity of the crude oil is less the greater the amount of gas dissolved therein, it is obvious that it is of first importance to maintain as nearly as possible the original gas pressure on the oil. Once the gas under pressure is allowed to escape it will be practically impossible to restore the original viscosity even by pumping natural gas back into the oil body because of the impracticability of securing intimate contact of the gas and oil, such contact being necessary to obtain complete absorption of the gas in the oil. In the original crude oil the gas has become thoroughly mixed and absorbed in the oil during the long period of time during which the oil and gas have been in contact and by the movements which have taken place between them while in the oil reservoir. As already indicated, the present methods of oil production are not conducive to a conservation of the gas pressure and hence to obtain the maximum possible production. When the gas pressure has been allowed to become low by dissipation, the viscosity of the oil has increased and thus its capacity to flow through the oil sands has also been reduced.

The present invention contemplates a method of oil production by which a body of oil is developed as a unit. The development of an oil body as a unit under the present laws requires that the developer own or control all of the surface land under which the oil body is located. In many cases it is not practicable for one party to have control of all of the surface land under which an oil body is located. Therefore, it is anticipated that the increased recovery of oil under the present invention and similar methods and a greater conservation of gas will act to stimulate National and State legislation which will require that all oil bodies that may be located shall be developed as a unit for the sake of conservation and economy.

To develop an oil field in accordance with the present invention it is necessary to locate quite definitely the position and boundaries of the oil body. The location of the oil body is usually effected by exploration. The term "exploration" is intended to include all the common and usual methods being used for locating oil wells. For

example, geological structures indicate the position of oil bodies and various types of drilling mechanism together with geological indications assist in locating oil bodies. Actual drilling of a comparatively large area will assist in locating oil bodies, and generally the definite boundary lines of an oil body are determined by drilling operations. While locating an oil body in accordance with the present invention it is very desirable that the area and boundaries of one or more gas bodies accompanying the oil body, be definitely located. Then the oil horizon or lower boundary should be located to find the position of the water body below the oil body.

Referring to Fig. 1, gas wells 10 should be drilled into what would be the top of the dome structure to locate the position of the gas body above the oil. When these wells are drilled precaution should be taken to keep the wells closed to the end that when the gas body is tapped by the well the gas may not escape and thus the pressure be maintained within the gas sand. Simultaneously with the drilling of the gas wells 10, oil wells 12 should be drilled to determine the boundaries of the oil body, and flowing wells 25 should be located in the oil body such that the wells will project into the upper portion of the oil body. As the oil wells are drilled they should be kept closed and any oil which might flow through the wells should flow only against a sufficient back pressure to maintain substantially the original oil pressure in the oil sands. Wells 14 should also be drilled to determine the water boundary of the oil pool or body for a purpose hereinafter mentioned.

As is well known the oil reservoir is usually found between impervious layers of rock, the upper layer being indicated at 16 and the lower layer at 18. All of the wells will, therefore, be projected through the upper layer 16. It is recognized that the dome structure shown in Fig. 1 is an ideal one but whether the oil body be found in a dome structure or in other forms the application of the invention will be substantially the same inasmuch as the relative positions of the gas, oil and water bodies will be substantially the same in all structures. The gas body has been indicated at 20, the oil body at 22 and the underlying water body at 24.

The oil wells and preferably also the gas wells 50 are provided at or near the bottom with an adjustable bottom flow bean valve diagrammatically indicated by 26 in Fig. 1. Referring to Figs. 3 and 4 wherein the well and valve structure are illustrated in detail, 28 indicates the well casing which 55 also serves in the illustrated example as oil education tubing, 30 the casing head, with associated valve mechanism including an adjustable back pressure valve or top flow bean 31, and 32 a packer at the bottom of the well. At the top of the packer 60 is secured a sleeve-like cap 34 having a valve seat 36 at its bottom for a needle valve 38 which is threadedly mounted in the cap as at 40 by suitable extensions leading therefrom. This valve is controlled from the top of the well by a hollow 65 valve stem 42, the same passing through the casing head and having a crank or the like 44 for adjusting the valve to its seat. The valve has an opening 46 extending axially therethrough so that oil and gas coming through the packer will pass 70 through the valve and into the valve stem. The valve stem exteriorly of the casing head is connected by suitable piping 48 to a pressure gauge 50 which is located intermediate the valve stem and a pump 52.

Inasmuch as the valve 38 has an opening extending therethrough and said opening is in direct communication with the hollow valve stem 42, the oil from the oil body is free to rise in the hollow valve stem and consequently the gauge 50 will indicate a certain pressure which, however, will not be the oil pressure existing on the oil body in the oil sands. The pressure indicated by the gauge will be less than the pressure existing on the oil body by an amount equal to the hydrostatic head of the column of oil which has risen in the hollow valve stem. Just what the height of the column of oil in the hollow valve stem is, will be uncertain of determination. If, however, air or gas is pumped into the hollow valve stem by the pump 52 sufficient to drive the oil out of the hollow valve stem, the actual pressure at the bottom of the well can be determined. As gas or air is pumped into the hollow valve stem the pressure on the gauge will rapidly rise as the height of the oil in the valve stem diminishes. When, however, all of the oil has been driven out of the valve stem, the pressure on the gauge will remain substantially constant due to the fact that the air or gas subsequently pumped into the valve stem will be free to enter a reservoir of relatively large cubical capacity and consequently the amount of gas forced into the reservoir by each stroke of the pump will be relatively small as compared with the capacity of the reservoir. It will, therefore be appreciated that the relatively constant pressure indicated by the gauge will be the pressure existing on the oil in its reservoir.

The pressure on the oil having been ascertained as aforesaid, the valve 38 is opened, whereupon oil and the dissolved gas will pass through lateral openings 54 above the valve seat and into the well. The valves 31 in the casing head are then so regulated that the oil will flow out of the well against a back pressure which will be somewhat less than that existing in the oil in the oil reservoir. In other words, the oil will pass into a region of somewhat reduced pressure above the valve 38 before passing out through the top of the well and the expulsive force of the expanding gas will carry the oil upwardly and out through the top of the well as will be readily understood.

As the oil is withdrawn from the oil reservoir the pressure of the gas therein will gradually fall. Any drop in pressure, however, will permit dissolved gas to pass out of the oil from whence it will find its way to the gas body 20 overlying the oil body. It has already been indicated that the viscosity of the oil is less the greater the amount of the dissolved gas therein. This invention therefore contemplates the maintaining of the original pressure or a high pressure approaching the original pressure on the oil body to prevent increase of the viscosity of the oil. This may be accomplished in different ways. A gaseous fluid, preferably natural gas, may be pumped directly into the gas body 20 through the gas wells which project into the same or it may be pumped into the oil sands by way of the oil wells. The natural gas pumped into the earth cavity in which the oil and gas are found, will preferably be that which escapes from the flowing oil wells, though if necessary, natural gas from other sources may be used. Natural gas is preferred to air because I have found that with some oils air seems to increase the viscosity of the oil and moreover air introduces certain complications in the processes of obtaining natural gasoline from the gas. By maintaining substantially the original gas pressure on the oil body, another advantage in addi-

tion to that of maintaining the original viscosity of the oil is obtained, namely that of preventing oil from the oil body from moving upwardly into the oil-dry sand in which the gas body occurs. Dry gas-sand will take up a comparatively large amount of oil and hold the same by capillary attraction so that its removal from the sand by ordinary methods of oil production is impossible. The described method of preventing the oil from moving upward into the dry gas sand is, therefore, an important feature of the invention.

As oil is withdrawn from the oil reservoir its level falls and hence the capacity of the gas chamber above the oil body also increases. Any increase in the capacity of the gas chamber is objectionable because it necessitates the pumping of a larger volume of gas into the same to maintain the original gas pressure on the oil body. For this and for other reasons hereinafter appearing the invention contemplates the maintaining of the oil level substantially constant and the same is accomplished by introducing water into the water wells 14 projecting into the oil body. The water is introduced comparatively slowly so as to permit it to spread under the entire oil area and thus to elevate the oil body as a whole. Furthermore, by introducing the water slowly the tendency for the water to channel through the sands toward the oil wells will be reduced to the minimum. It will also be apparent that if there is no avenue of escape of water to the outlying sands, the amount of water introduced should equal only the amount of oil drawn off from the oil body.

The water supplied to the water wells will preferably be the same type of salt water as that which occurs naturally on the oil fields, and this water may be handled through a single pumping station. It will be apparent that only a comparatively low pressure will be required because there are balanced hydrostatic heads in the oil wells and water wells. The water wells are deeper than the oil wells and due to the fact that the water has a higher specific gravity than the oil, there would be a natural tendency for the oil to be forced out of the sands through the oil wells if the resistance of the flow of water through the oil sands were not too high. Therefore in pumping the water into the wells 14 the only pressure which is required is that pressure which is necessary to overcome the resistance of the flow of water through the oil sand. Furthermore, it will be seen that the deeper the wells the greater will be the advantage of recovering oil by the balanced heads of water and oil because the higher hydrostatic heads of water tend to create a greater pressure for forcing the oil out of the ground. This is very important because by this method it is possible to force oil out of the sands which are very far from the surface of the earth where it is impracticable to remove oil from the wells by pumping due to the mechanical limitations of the ordinary pumping mechanism.

When water is introduced into the oil sand around the horizon of the oil body it may have to travel many feet or many miles before it will materially affect the pressure of the oil in some portions of the body. However, if the pressure is maintained throughout the oil body and the gas pressure is maintained above the oil body, by a slow gradual process the water may be forced through the oil sand to drive the oil out of the sand through the wells. Furthermore, as the water advances through the sand and past out-

lets which formerly served as an outlet for oil, this oil outlet may be used as a water inlet.

There will be a comparatively large number of oil wells as distinguished from water wells, the 5 number of oil wells being such that substantially all parts of the oil body will have an outlet. The water will, preferably, be introduced simultaneously through all of the wells 14 surrounding the oil body and oil may be simultaneously flowed 10 through all or the greater part of the oil wells projecting into the oil body.

I have previously indicated that the original rock pressure may be maintained on the oil body by introducing gas through the gas wells 10. It 15 should be pointed out, however, that the introduction of water through the water wells may under certain conditions serve to maintain substantially the original rock pressure on the oil body. This will become more readily apparent 20 when it is remembered that one factor tending to cause a reduction of the pressure on the oil body is the fact that the capacity of the gas chamber above the oil body increases as the level of the oil falls due to its withdrawal from the 25 oil body. If, however, the level of the oil body is maintained substantially constant by the introduction of water below the oil body, as previously indicated, there will be no reduction of pressure in the gas chamber from this cause. 30 The only two other factors which would tend to cause a reduction of the pressure in the gas chamber are the dissipation of the gas through the gas wells and the escape of gas with the oil through the oil wells. However, inasmuch as the 35 gas wells are kept closed there will be no escape of gas through them. The escape of free gas from the gas chamber by way of the oil wells will be negligible because of the relatively high back pressure maintained in the oil wells. It 40 will, therefore, be seen that the rock pressure on the oil body may be maintained in three different ways; namely by introducing gas under pressure through the gas or oil wells; by introducing water to meet the oil body through the water wells, or 45 by employing both methods simultaneously. Further, it will be apparent upon reflection that those oil wells which are projected farthest into the oil body will eventually begin to flow water as the water level rises, assuming that water is 50 being introduced below the oil body for the purpose of maintaining its upper level constant. When this occurs such wells will be stopped or may be employed as water wells for the introduction of water. If, on the other hand, no change 55 is made in the water level, some of the oil wells will eventually become gas wells as the oil level falls. These wells will then be stopped or may be utilized for pumping gas into the gas chamber.

From the above description it will be seen that I

have provided a method of and apparatus for developing oil fields which will permit the extraction of the maximum amounts of oil from the oil field and that the invention makes full use of an important property of the original oil, a 5 property which has heretofore not been availed of in the development of oil fields; namely, the property that oil in its original condition in its rock chamber has a very low viscosity due to the natural gases dissolved therein. As previously indicated, the low viscosity of the oil in the oil body permits it to flow with relatively great freedom through the oil sands.

Another important advantage resulting from the extraction of oil according to the present invention is that the amount of gas produced with each barrel of oil is reduced to a minimum. Other advantages will be apparent to those skilled in the art.

While the invention has been described with 20 considerable particularity of detail, it is to be understood that no limitations on the invention are intended except as may be expressed by the appended claims.

What is claimed as new is:

1. A method of extracting oil from an oil field having a body of gas overlying a body of oil in an earth cavity, which comprises providing one or more wells which penetrate the oil body through which oil may flow to the earth's 30 surface, squeezing the oil body by maintaining gas pressure above the oil body and water pressure below the oil body sufficient to force the oil through the wells to the surface, holding a back pressure against the oil entering a well sufficient 35 to maintain gas in solution in the oil body as oil is withdrawn from the cavity, and holding an adjustable back pressure on the oil in the well sufficiently less than that held on the oil entering the well to permit gas to escape from solution in 40 the oil in the well at a controlled rate thereby liberating expulsive energy of the expanding gas for lifting the oil to the top of the well.

2. A method of extracting oil from a body of oil in an earth cavity, which comprises providing 45 one or more wells which penetrate the oil body through which oil may flow to the earth's surface, holding an adjustable back pressure against the oil entering a well sufficient to maintain gas in solution in the oil body as oil is withdrawn from 50 the cavity, and holding an adjustable back pressure on the oil in the wells sufficiently less than that held on the oil entering the well to permit gas to escape from solution in the oil in the well at a controlled rate thereby liberating expulsive 55 energy of the expanding gas for lifting the oil to the top of the well.
